CLAIM

The ornamental design for a shower hanger support for standard and hotel hangers, as shown and described.

DESCRIPTION

FIG. 1 is a top plan view of a shower hanger support for standard and hotel hangers showing my new design;

FIG. 2 is a front elevational view thereof;

FIG. 3 is a bottom plan view thereof;

FIG. 4 is a rear elevational view thereof;

FIG. 5 is a left end elevational view thereof;

FIG. 6 is a right end elevational view thereof;

FIG. 7 is a perspective view shown in operational attached position, the shower head shown in broken lines for illustrative purposes only;

FIG. 8 is a perspective view shown in retracted attached position, the shower head shown in broken lines for illustrative purposes only.

FIG. 1-

FIG. 2-

FIG. 3-

FIG. 4-

FIG. 5-

FIG. 7-

FIG. 8-
